UNITED STATES PATENT OFFICE.

JOHN W. HARRINGTON, OF HOUSTON, TEXAS.

DESIGN FOR A POWDER-BOX.

58,905.

Specification for Design.

Patented Sept. 6, 1921.

Application filed June 14, 1920. Serial No. 389,027. Term of patent 14 years.

To all whom it may concern:

Be it known that I, JOHN W. HARRINGTON, a citizen of the United States, residing at Houston, in the county of Harris and State of Texas, have invented a new, original, and ornamental Design for a Powder-Box, of which the following is a specification, reference being had to the accompanying drawing, forming part thereof.

Figure 1 is a plan view of a box showing my new design.

Fig. 2 is an edge view thereof, and
Fig. 3 is a perspective view thereof.

I claim:

The ornamental design for a powder box
as shown.

JOHN W. HARRINGTON.
